Patented Sept. 3, 1918.

ATTORNEY

UNITED STATES PATENT OFFICE.

FREDERICK G. ROTTMUND, OF LANCASTER, PENNSYLVANIA.

BINDER-CUTTER.

1,277,487.

Specification of Letters Patent. Patented Sept. 3, 1918.

Application filed October 12, 1916. Serial No. 125,228.

To all whom it may concern:

Be it known that I, FREDERICK G. ROTTMUND, a citizen of the United States, residing at Lancaster, in the county of Lancaster and State of Pennsylvania, have invented certain new and useful Improvements in Binder-Cutters, of which the following is a specification.

This invention relates to cigar manufacturing mechanism and particularly to binder cutters.

The invention aims primarily to provide a simplified and improved device for cutting the binders or wrappers for cigars, and embodies an improved construction whereby the cutting mechanism may be easily actuated, and which may be adjusted to cut wrappers of various lengths.

Further objects reside in providing a bunch rolling plate or table with a cutting mechanism, the latter being arranged so as to be moved out of cutting position to permit of the table being used as a bunch rolling surface, which has the cutting mechanism so arranged as to be capable of readily operating upon leaves placed upon the plate or table, which will prove a time, labor, and material saver, and which will prove thoroughly efficient in the attainment of the various ends set forth.

The invention has for a still further object to provide a device of this character which is of extremely simple construction, which is composed of but few inexpensive and readily assembled parts, all so constructed and arranged as to prevent wear, breakage or derangement of the device, and which will prove practical and efficient in use.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:—

Figure 1 is a top plan view of a bunch rolling plate or table constructed in accordance with the invention and having applied thereto an improved cutting device, the latter being shown in inoperative position;

Fig. 2 is a side elevation of the device illustrated in Fig. 1;

Fig. 3 is an enlarged plan view of the cutter frame;

Fig. 4 is a fragmentary sectional view illustrating the manner of connecting the cutter frame to the table; and

Fig. 5 is an enlarged sectional view taken upon line 5—5 of Fig. 1.

Referring now more particularly to the drawings, 6 represents a bunch rolling plate or table, the latter being of any suitable or approved size and type, and is provided with the usual smooth unobstructed upper surface so as to permit of perfect rolling of the bunches or cigars.

Associated with the table 6 is a knife carrying frame indicated generally at 7, and capable of moving into and out of engagement with the said table to cut into predetermined lengths, the wrappers placed thereon. To support the frame upon the table, arms 8 are bolted as at 9 to the extremities of the table at the rear end thereof. These arms project rearwardly from the table and extend upwardly therefrom and provide alined openings, within which a shaft 10 is supported. As is illustrated in Figs. 2 and 4, ball bearings 11 are arranged within the openings in the arms so that the shaft may be free to rotate in the arms.

The frame 7 is formed in the present instance of angle bars of substantially rectangular shape, the said frame being of a size equal to approximately the length and width of the board or table 6. Secured to the frame 7 adjacent one end and extending laterally thereof is a bar 12, to which is bolted or in any other preferred manner secured a knife blade 13, the latter being of very thin construction. Secured to the frame 7 near the opposite end thereof and disposed in parallel relation to the above mentioned bar is a second bar 14, the same carrying a cutting blade 15 similar to the blade 13. The longitudinal angle bars of the frame 7 are slotted as at 16 to accommodate bolts 17 secured to the bar 14, the construction permitting of longitudinal adjustment of the knife carrying bar. The frame 7 is secured to the shaft 10 by means of rearwardly extending arms 18.

A rearwardly extending lever arm 19 is secured as by means of a set screw 20 to the shaft 10 intermediate the ends thereof and

an adjustable weight 21 is arranged for movement longitudinally of said lever. The weight 21 is adjusted so as to slightly overbalance the frame 7 projecting forwardly 5 from the shaft, so that the shaft will be normally maintained with the frame 7 projecting upwardly or out of engagement with the upper surface of the plate or table 6.

The bunch or cigar rolling table is provided with laterally disposed parallel slots, within which the downwardly projecting blades 13 and 15 of the frame 7 are adapted to extend. The slots are indicated generally at 22, and metallic strips 23 are set into suitable shallow notches made in the upper face of the table adjacent the longitudinal edges of the said slots. These strips may be fastened to the table so as to set flush with the upper face thereof, and the openings 24 formed in the said strips are of sufficient width to permit of the blades 13 and 15 entering the same. The openings 24 are widened as at 25 adjacent their rear end, the said widened portion being so positioned 25 as to receive the rear edges of the blades 13 and 15 when the latter are lowered upon the table. It will be observed that there are several of the slots 22 adjacent that end of the table with which the adjustable blade 15 is 30 adapted to coöperate, and it is thus obvious that adjustment of the plate 15 may be freely made longitudinally of its supporting frame, so that it will be received within any one of the spaced slots 22 at the adjacent end 35 of the table.

To permit of the shaft and the cutting frame 7 being adjusted relative to the upper face of the table 6, the arms constituting the supporting brackets 8 are rendered adjustable. The inner ends of the arms 8 are provided with laterally extending elongated slots 25', through which bolts projecting outwardly from the edges of the table extend. The nuts 27 upon these bolts, when tightened, bind the arms 8 against the edges of the board, but when loosened, permit of the arms rocking upon their supporting bolts 9. In this manner, it is seen that adjustment of the cutting frame toward and away from the table 6 may be readily made.

It will be observed that the table 6 is provided with spaced apertures, and it will be understood that the device may be adapted for use in connection with vacuum means for 55 maintaining the wrappers upon the table during the cutting operation.

From the foregoing, it is apparent that I have provided an extremely simple and yet thoroughly efficient means for carrying out 60 the ends set forth. The knife 15 is first adjusted so as to cut the wrappers placed upon the table into proper or desired lengths. The tobacco leaves placed upon the table are maintained in proper position in the

usual manner, and the frame 7 is then 65 grasped by the operator and swung downwardly. The knives enter their respective grooves, and sever the leaves. It will be observed that the blades 13 and 15 have their cutting edges inclined from their rear to 70 their foremost ends, whereupon a shearing action upon the wrappers is produced when the frame is lowered. It will also be observed that the widened portion 25 in the strips secured to the table, enables the rear 75 edges of the knife blades being properly aligned with the slots during the cutting operation. After the wrappers have been cut, the frame is released, whereupon the weight 21 swings the same upwardly and out of 80 engagement with the table. The table may then be used for rolling or bunching or such other operations as are necessary in cigar manufacture.

While the present is a disclosure of what 85 I believe to be the preferred embodiment of the invention, it is to be understood that the invention is not limited thereto, as various changes may be made in the construction, arrangement and proportion of parts, without departing from the scope of the invention, as defined in the appended claims.

What is claimed is:—

1. In a device for cutting binders, a table having spaced slots, said slots being widened 95 at certain points in their length, a cutter frame capable of moving toward or away from said table, knives on said frame adapted to enter said slots, the said knives being broader at one end than at the other, and the said broadened ends of said knives being adapted to enter the said widened portions of said slots when the said frame approaches the said table.

2. In a device for cutting binders, a table 105 having spaced longitudinally disposed slots therein, said slots being widened at certain points in their lengths, a frame pivoted at one end to said table and being capable of swinging downwardly upon the latter, 110 means for adjusting the pivotal support of said frame toward or away from said table, knife blades carried by said frame and being adapted to enter said slots, the said blades being broader at one end than at the other, 115 and the said broadened portions of said blades being adapted to enter the widened portions of said slots.

3. In a device for cutting binders, a table having spaced longitudinally disposed slots 120 therein, the said slots being widened at certain points in their lengths, brackets adjustably mounted at one end of said table, a shaft supported by said brackets the said brackets being capable of being adjusted so 125 as to move said shaft toward or away from said table, a frame secured at one end to said shaft, blades depending from said

frame and being adapted to enter said slots, the said blades being broader at one end than at the other and having straight cutting edges, and the broadened ends of said blades being adapted to register with the widened portions of said slots.

In testimony whereof I affix my signature in presence of two witnesses.

FREDERICK G. ROTTMUND.
